UNITED STATES PATENT OFFICE.

FRANCISCO PRAT BOSCH, OF BADALONA, SPAIN.

ROTARY PUMP.

1,321,706.

Specification of Letters Patent.

Patented Nov. 11, 1919.

Application filed December 11, 1915. Serial No. 66,376.

To all whom it may concern:

Be it known that I, FRANCISCO PRAT BOSCH, a subject of the King of Spain, residing at Badalona, Barcelona, in the King-
5 dom of Spain, have invented certain new and useful Improvements in Rotary Pumps; and I do hereby declare the following to be a full, clear, and exact description of the invention, such as will enable others skilled
10 in the art to which it appertains to make and use the same.

This invention relates to improvements in rotary pumps in which a drum provided with paddles is adapted to revolve in a casing, in eccentric relationship to the interior thereof. In pumps of this character the paddles are arranged to slide in slots formed in the drum in such a manner that their ends are always kept in contact with the
15 inner surface of the casing whereby a more efficient propulsion of the liquid is attained.

The main object of this invention is to provide a pump in which the paddles of the drum are constantly kept in contact with the
20 inner surface of the casing by the combined action of the centrifugal force imparted to the paddles and by the pressure of the liquid behind the paddles, the centrifugal force being the predominating factor in the
25 attainment of the above result.

Another object of this invention is to provide a pump in which the suction and discharge of the liquid are produced in two or more working chambers arranged symmetrically with respect to the drum, whereby an
30 equalization of pressures to which the shaft of the pump is subjected is attained.

In accordance with this invention, the drum is formed at its periphery with a plurality of slots inclined with respect to the corresponding radii of the drum and in which the paddles are adapted to slide. Each slot is cut away at its forward end exposing a portion of the forward end of
35 the blade. The drum is also formed with a plurality of grooves whereof each communicates with the bottom of a slot. The inner surface of the pump-casing may be of such shape that it will form with the
40 drum two or more working chambers, each of these communicating with the suction and discharge pipes. The working chambers are formed with a cylindrical surface which at the central part of the chambers

is concentric with the surface of the drum
55 and diverges therefrom or converges therewith at the junctions of the chambers with the suction and discharge conduits.

Further objects and novel features of this invention will appear from the following 60 detailed description, reference being had to the accompanying drawings, in which:

Figure 1 is a cross section of a rotary pump according to this invention.

Fig. 2 is a sectional view of the same on 65 the line II—II of Fig. 1.

Figs. 3 and 4 are front and side views respectively of the drum without the paddles.

Fig. 5 is a sectional view of a modified 70 form of a pump on the line V—V of Fig. 6, and

Fig. 6 is a sectional view of the same on the line VI—VI of Fig. 5.

Referring to Figs. 1 to 4, 1 designates a 75 casing and 16 a cover which may be secured to the casing by means of screws passing through the openings 25. The casing 1 and the cover 16 are provided with hubs 15—17, respectively, in which is journaled the shaft 20, 21 of the wheel. The hub 15 receives a stuffing box 19 and the shaft 20 is formed with an outer extension for receiving the rotary movement. The
80 casing 1 is further provided with a suction-pipe 2 and a discharge pipe 3.

The casing 1 is also formed with two lateral conduits 4—5 which establish communication between the pump body and the
85 pipes 2—3.

A drum 7 is arranged eccentrically in the casing 1, and is tangential to the inner surface of the casing at the point 6, while the remainder of its outline forms with the casing a chamber 8 which corresponds to the
90 eccentricity and determines the capacity of the pump.

In the pump shown in Figs. 1 and 2, the drum 7 is provided with four paddles 11—12—13—14, slideable in grooved slots 28 formed in the drum 7 and which are closed laterally by disks 9—10, secured to each face of the drum 7 by means of screws 22, thus forming a unitary structure. The slots 28 are cut away at their forward end, as at
95 27, and the bottom of each slot is in communication with a groove 26. The paddles 11—12—13—14 are preferably beveled and

are so arranged as to form an acute angle with the direction of their movement. This angle may, of course, be varied according to the pressure which it is desired to maintain at the end of the paddle.

By revolving the drum 7 in the direction of the arrow 24, suction is created behind the paddle which occupies the position 12 and the discharge of the fluid in front thereof. This is due to the fact that the paddle is in contact with the surface 6' until it comes to the conduit 5 which communicates with the pipe 3 for the discharge of the liquid.

15 The water drawn by the pump fills the groove 26 and arriving at the slot 28 it acts upon the paddle forcing its edge against the inner surface of the casing. The centrifugal force, developed by the rotation of the 20 drum also forces the paddle against the casing. In this manner the edge of the paddle is always kept in contact with the inner surface 6' of the casing 1, and furthermore the contact surface between the paddle 25 and the casing is rendered water-tight without producing any appreciable attrition. On reversing the direction of rotation of the drum 7 a vacuum is produced in the slot 28, and the paddle is forced thereinto rendering 30 the pump inoperative, and thereby avoiding the serious injuries which usually arise from a reversal of the direction of rotation.

In the modified form of the improved 35 pump shown in Figs. 5 and 6, the casing 1 and the drum 7 form two working chambers 43 and 44, whereof the cylindrical surfaces 46 are symmetric with the drum 7. The working chambers 43—44 communicate with 40 suction and discharge chambers. In the chamber 44 suction is transmitted by the pipe 2 and the discharge by the chamber 37 which communicates with the conduit 36 and the discharge pipe 3.

45 The liquid enters the working chamber 43 through the chamber 34 communicating through conduit 33 with the suction pipe 2, and the discharge end of the working chamber 43 communicates directly with discharge 50 pipe 3. Therefore, the liquid suction pipe 2 communicates with all working chambers and the same applies to the discharge pipe 3.

The surfaces 46 of the working chambers merge into the surfaces 49, 50 forming the 55 dead points of the paddles, the latter surfaces merging into the eccentric surfaces 47, 48, all of these surfaces forming a unitary cylindrical inclosure for the drum.

The pump may, of course, be formed with 60 more than two working chambers, care being taken to properly balance the pressures

upon the paddles and the shaft of the pump and to minimize attrition.

It is obvious that various modifications may be effected in the apparatus hereinbefore described without in any way departing from the scope of this invention.

What I claim is:

1. In a rotary pump, the combination with a casing having inlet and outlet ports 70 for the liquid fluid, of a rotary drum forming with the casing a working chamber, said drum provided in its periphery with a plurality of slots inclined relatively to the corresponding radii of the drum, a plurality of paddles adapted to slide in said slots, each of the slots communicating in its lower portion with the exterior of the drum and said paddles being free to engage against the drum only by the combined action of 75 centrifugal force and of the force developed by the friction between the end of the paddle and the casing.

2. In a rotary pump the combination with a casing having inlet and outlet ports for 80 the liquid, of a rotary drum provided in its periphery with a plurality of slots inclined in relation to the corresponding radii of the drum, a plurality of free paddles with the ends beveled which slide in said slots, 85 said casing and drum forming a plurality of working chambers each one of which communicates by one end with the inlet port of the liquid and by the other end with the discharge port.

3. In a rotary pump, the combination with a casing having inlet and outlet ports, of a rotary drum provided in its periphery with a plurality of slots, a plurality of free paddles with beveled ends in said slots 100 adapted to engage against the inner surface of the casing to propel the liquid, each slot forming with its corresponding radius an angle which increases with decrease in the peripheral velocity of the drum, said slots being cut away at their forward ends, and each having a longitudinal groove extending to the bottom of the slot, said casing forming in combination with the drum a plurality of working chambers, each one of 105 which communicates at one end with the inlet port and at the other end with the outlet port, each working surface being formed in its central part by a cylindrical surface concentric with the drum, and at 110 both ends by surfaces extending from the contact point between the casing and the drum to the surface of the working chamber.

In testimony whereof, I affix my signature. 120

FRANCISCO PRAT BOSCH.
